ORGAN

Winsor D. White, Jr., Blowing Rock, N.C., assignor to D. H. Baldwin Company, Cincinnati, Ohio, a corporation of Ohio

Filed Sept. 3, 1965, Ser. No. 86,821

Term of patent 14 years

(Cl. D56—2)

The single figure is a front, top and left side perspective view of an organ, showing my new design, the right side being substantially a mirror image of the left side except that the grille near the bottom is omitted. The legs as illustrated are rectangular in cross-section at all points. The manuals fragmentarily shown are continuous within the dot-dash boundaries indicated. The grille fragmentarily shown is continuous across the bottom front panel within the boundaries indicated.

I claim:

The ornamental design for an organ, substantially as shown and described.
